UNITED STATES PATENT OFFICE

2,566,452

NARCOTICS CONTAINER AND BILLFOLD FOR
PHYSICIANS

Herbert H. Kersten, Fort Dodge, Iowa

Application October 21, 1949, Serial No. 122,663

1 Claim. (Cl. 150—35)

1

This invention relates to a novel construction of billfold for use by physicians and provided with means for containing a normal supply of narcotics as ordinarily required to be carried by physicians thus affording a means whereby valuable narcotics may be conveniently carried by a physician on his person eliminating the danger of loss which exists where narcotics are carried in instrument bags.

It has frequently occurred that instrument bags have been stolen from physicians by narcotic addicts seeking to obtain narcotics and which not only results in a loss of the narcotics but also in the loss of valuable instruments and other valuables carried in a physician's case.

Accordingly, as it is usually necessary for practicing physicians to carry small amounts of narcotics for emergency cases, it is a primary object of the present invention to provide a means whereby such narcotics may be carried conveniently and safely without danger of loss and by the use of which narcotic addicts will be discouraged from attempting to obtain narcotics by stealing physicians' cases.

Still a further and particularly important object of the present invention is to provide a container for narcotics adapted to be carried upon the person thereby eliminating the danger of loss or injury to narcotics which may readily occur if left in an instrument bag in an automobile during sub-freezing weather.

Various other objects and advantages of the invention will hereinafter become more fully apparent from the following description of the drawing illustrating one presently preferred embodiment thereof, and wherein:

Figure 1 is a plan view looking toward the inner side of the narcotics container and billfold and showing the container and billfold in an extended, open position;

Figure 2 is an enlarged longitudinal sectional view taken substantially along a plane as indicated by the line 2—2 of Figure 1;

Figure 3 is an enlarged fragmentary longitudinal sectional view showing an end portion of the billfold-container in a closed position, and

Figures 4 and 5 are enlarged cross sectional views taken substantially along planes as indicated by the lines 4—4 and 5—5, respectively, of Figure 1.

Referring more specifically to the drawing, the billfold-container in its entirety and comprising the invention is designated generally 6 and includes a body portion, designated generally 7 which may be formed of any suitable, flexible

material such as is conventionally used for making billfolds, usually leather, and which includes an elongated strip of such flexible material which is folded back upon itself intermediate of its ends to provide an inner ply 8 and an outer ply 9. The plies 8 and 9 are connected at a point adjacent to but spaced from the intermediate portion of said body member by a row of stitching 10 which is disposed transversely of the plies and which separates the intermediate portion of the body member 7 from the end portions thereof, forming the plies 8 and 9, said intermediate portion forming a sleeve portion 11 which extends transversely of the billfold-container 6 and which is located at one end thereof. The sleeve 11 may be closed in any suitable manner at its lower end as by means of a disc 12 of a corresponding material which may be stitched or otherwise secured to the lower end of the sleeve 11, as indicated at 13.

The intermediate portion of the inner ply 8 is lapped and stitched as seen at 14 along a line transversely of said ply to provide a transverse sleeve portion 15 which is located intermediate of the ends of the body member 7 and on the exterior side of the inner ply 8. The ends of the plies 8 and 9, constituting the end of the body member 7 located remote to the sleeve 11 are stitched as seen at 16 along a line transversely of the body member and the complementary bottom longitudinal edges of the plies 8 and 9 are stitched together along the line 17 so that the plies 8 and 9 will combine to form an elongated open top compartment 18 which extends substantially the length of the billfold container 6 and which may be utilized similar to a conventional wallet for containing paper money.

The sleeve 11 is adapted to contain a tubular container 19 which is sized to fit snugly therein and to extend substantially from end-to-end thereof. The container 19 is provided with an internally threaded open end, disposed adjacent the upper open end of the sleeve 11 and which is normally closed by an externally threaded plug 20. The container 19 is adapted to contain two small containers or vials of liquid narcotics, which vials are shown in Figure 4 and designated generally 21. The vials 21 are adapted to be spaced one above the other by a spacing disc 22 interposed therebetween and are sized to substantially fill the container 19. However, if desired, a single vial 21 of proper size could be mounted in the container 19. It will be readily apparent that the contents of the vials 21 are readily accessible to the physician by removing the threaded

plug 20 and tilting or inverting the sleeve 11 so that the vial or vials 21 can be readily withdrawn therefrom.

The intermediate sleeve 15, which may be left open at its lower end, is adapted to snugly receive an elongated cylindrical container 23, similar to the container 19 and which snugly fits into said sleeve 15 and has an internally threaded open end disposed adjacent the upper end of the sleeve 15 and adapted to be normally closed by an externally threaded plug 24. The container 23, like the container 19 has a closed bottom and is of a proper internal diameter and length to receive in relatively snug fitting engagement therein a similarly shaped container 25 which is adapted to contain narcotics in a dry, preferably tablet form, as indicated by the tablets 26 and the open upper end of which is normally closed by a plug or closure 27.

The container 23 is supported in the sleeve 15 by shank portions 28 of a plurality of eye members 29, which shank portions extend through openings 30 in the portion of the sleeve 15 which is located remote to the stitching 14 for positioning the eye members 29 externally of the sleeve 15. The terminals of the shank portions 28 are anchored in longitudinally spaced portions of the container 23, as seen at 31 so that the eye members 29 function to support the container 23 in the sleeve member 15 and are in turn supported by said container on the sleeve member. A plurality of conventional transparent card holders 32 each comprising two transparent strips which are connected along their side edges and one end by a U-shaped binder 33 are swingably supported on the billfold-container 6 by the eye members 29. As seen in Figure 1, the intermediate portion of each binder 33 is provided with spaced openings 34 in which the eye members 29 are loosely engaged for swingably mounting the transparent card holders 32 on the inner side of the body 7. The card holders 32 may be utilized for carrying any cards normally carried in a wallet, including narcotics blanks or records. Additionally, the body member 7, between the sleeves 11 and 15 includes a small, ply 35 which is secured along its side edges and one end by a binding 36 to the exposed side of the inner ply 8 to combine therewith to form a pocket 37, primarily intended to be used for containing a narcotics record 38 or record blanks and so that it will be always conveniently available to the physician to maintain complete and accurate records of all narcotics used.

It will be noted that the sleeve 15 is slightly 55

smaller in diameter than the sleeve 11 and that the end portion of the body 7 of the billfold, remote to the sleeve 11, is shorter than the other end portion thereof so that when the billfold is closed the sleeve 11 will be located beyond the end of the billfold 6, containing the stitching 16 to thereby reduce the bulkiness of the billfold-container and to enable it to be most conveniently carried in a garment pocket.

10 Various modifications and changes are contemplated and may obviously be resorted to, without departing from the spirit or scope of the invention as hereinafter defined by the appended claim.

I claim as my invention:

A combination billfold and narcotics container comprising an elongated billfold or wallet formed of a flexible material having an integral transverse sleeve at one end thereof and an integral transverse sleeve intermediate of its ends each formed of an integral part of the billfold or wallet material, a pair of narcotic containers one disposed in and substantially filling each of said sleeves and each having an open end, and removable closures for the open ends of said containers, said wallet or billfold being formed of a single elongated strip of the flexible material folded upon itself substantially intermediate of its ends to form inner and outer plies, said plies being stitched together along a transverse line adjacent the intermediate portion of the strip to form the sleeve located at the end of the billfold, one of said plies constituting the inner ply having a lapped and stitched portion disposed on its external side and forming said intermediate sleeve.

HERBERT H. KERSTEN.
